UNITED STATES PATENT OFFICE.

HOWARD G. ELLIS, OF WATERTOWN, MASSACHUSETTS, ASSIGNOR TO HOOD RUBBER CORPORATION, OF WATERTOWN, MASSACHUSETTS, A CORPORATION OF MASSACHUSETTS.

DESIGN FOR A VEHICLE-TIRE.

48,348.

Specification for Design.

Patented Dec. 28, 1915.

Application filed December 28, 1914. Serial No. 879,419. Term of patent 14 years.

To all whom it may concern:

Be it known that I, HOWARD G. ELLIS, a citizen of the United States, residing at Watertown, in the county of Middlesex and State of Massachusetts, have invented a new, original, and ornamental Design for Vehicle-Tires, of which the following is a specification, reference being had to the accompanying drawing, forming a part thereof.

In this drawing Figure 1 is a perspective

view of a vehicle tire showing my new design; and Fig. 2 a developed plan of a portion thereof on a larger scale.

I claim:

The ornamental design for a vehicle tire, as shown.

HOWARD G. ELLIS.

Witnesses:

J. R. MOTT,
H. C. PERLEY.
